UNITED STATES PATENT OFFICE.

LEVI K. FULLER, OF BRATTLEBOROUGH, VERMONT, ASSIGNOR TO THE
ESTEY ORGAN COMPANY, OF SAME PLACE.

DESIGN FOR AN ORGAN-CASE.

SPECIFICATION forming part of Design No. 20,342, dated November 18, 1890.

Application filed July 15, 1890. Serial No. 358,840. Term of patent 7 years.

To all whom it may concern:

Be it known that I, LEVI K. FULLER, of Brattleborough, in the county of Windham and State of Vermont, have invented and produced a new and original Design for Chapel-Organ Cases, of which the following is a specification.

The present design relates to the cases of what are known as "chapel-organs," which are finished front and back; and it consists in the ornamentation of such chapel-organ cases.

The design is illustrated in the accompanying photographic representations, in which—

Figure 1 is a perspective view of the case, showing the front and one side; and Fig. 2 is a perspective view of the case, showing the back and one side.

The leading features of this design consist in the ornamental lattice or scroll work, which appears in the front board of the key-projection in the music-desk and in the back of the case; in the ornamental rosettes which appear at the front board and ends of the case, and in the ornamental balustrades which surmount the ends of the case.

Referring to Fig. 1, A is the front board of the case; B, the front board of the key-board projection; C, the music-desk; D, the end of the key-board projection, and E one end of the case.

The front board A of the case is divided into three rectangular panels, the two side panels being of the same size and smaller than the central panel. The central panel is without ornament. Each side panel is ornamented in its center by a round blazed rosette *a*, as shown.

The front board B of the key-board projection has two narrow horizontal panels *b*, each of ornamental open or lattice work, as shown. The lattice-work of each panel is made up of a series of separated groups of two concentric rings each. The outer ring of each group is tangential to the upper and lower margins of the panel. All of the rings are connected together and with the side margins of the panel by narrow horizontal bands or fillets, as shown, which, it will be noted, do not cross the small inner rings. Each small inner ring, as shown, has on its outer periphery a plurality of projecting tongues occupying the half an-

nular spaces between the inner and outer rings. A plurality of small rings exterior to the concentric rings are embraced in the design, each small ring being tangential to the horizontal narrow bands or fillets and to one of the horizontal margins of the panel, as shown.

The music-desk C is of ornamental lattice or scroll work, as shown. The lattice or scroll work is characterized by an ornamental border of an irregular rectangular shape and two inner rings tangential with each other and with the border, as shown. Within each of these rings is a smaller concentric ring connected with the outer ring at intervals of ninety degrees by narrow bands or fillets, as shown. Within each inner ring is an ornamental volute or scroll, as shown. The exterior margin of the border of the music-desk is ornamented at the sides, top, and upper corners, as shown. At the rear of the music-desk (see Fig. 2) are two ornamental corbels or brackets *c* of scroll-work. Each end D of the key-board projection rests upon a column F, the end D being, as it were, the entablature of the column. The column F rests upon a plinth *d*, projecting forwardly from the base G of the organ-case, as shown. The base of the column is cylindrical in shape, and is ornamented by annulets and a fluted band, as shown. The shaft of the column is wreathed or twisted, as shown. The capital of the column is composed of an astragal, which surmounts the shaft, a spherical body portion with central annulets, and a diminished abacus, as shown. The end D of the key-board is characterized by the shape of its front edge and its ornamentation. The capital of the column F is immediately surmounted by a molding or scotia, which constitutes the base of the end D, as shown. From this base the front edge of the end D springs in an ogee curve which terminates in a short vertical portion of the edge. This vertical portion extends just above the bottom of the front board B, and terminates in an ogee curve which extends to above the front board B. An inclined portion of the edge extends from this second ogee curve to the end E of the case, as shown.

The side face of the end D is ornamented

near the top by a lamp-mat bracket *o*, which in turn is ornamented on both faces (see both Figs. 1 and 2) by a stellated ornament. Immediately below this bracket the end *D* is ornamented by a wreath ornament *e*, as shown. Beneath this wreath ornament is a group of horizontal lines constituting a linear ornament *f*, which also extends across the front edge of the end *D*. Below the linear ornament *f* the end *D* is further ornamented by a semicircular groove and a pyramidal ornament, as shown. The vertical portion of the front edge of the end *D* is ornamented with a stellated ornament, and the upper ogee and inclined portions of the edge of the end *D* are ornamented by longitudinal linear grooves, as shown.

Each end *E* of the case includes a vertical narrow rectangular panel *g*, extending from the base *G* of the case to near the top, and a square panel *h* at the top. The end *E*, near the upper part of the panel *g*, is ornamented by two brackets *i*, having a fluted bar between them, each bracket being in turn ornamented on its outer face by a stellated ornament, as shown. The upper square panel *h* is ornamented by a round blazed rosette *a*, (similar to the rosettes on the front board *A*), as shown. The upper and lower rails bordering the panel *h* are ornamented by straight lines, as shown. Each end *E* is surmounted by a balustrade *H*, which projects above the body of the organ-case. Each balustrade has an upper rail supported by posts at each end and by balusters between the posts, each baluster being characterized by spherical ornaments, as shown. The upper rail of each balustrade is ornamented at each end by a finial, as shown.

Referring to Fig. 2, *I* is the back of the organ-case. The back *I* is divided into eight panels arranged in two horizontal rows. Each of the four panels *m* of the lower row is an elongated rectangle having a greater height than width. Each of these four panels *m* is ornamented near its top by two straight lines and two rows of indentations or flutes, as shown. The outer stiles and the meeting stiles of the panels are ornamented by longitudinal lines, as shown. Each of the four panels *n* of the upper row of panels is square, and each panel is composed of ornamental reticulated or lattice work. In its generic features each of these lattice-work panels *n* resembles the lattice-work of the panels *b* of the front board *B* and of the music-desk *C*. Each lattice-work panel *n* is made up of two concentric rings,

the outer of which is tangential to the margins of the panel, the inner ring being connected with the outer ring at intervals of 60 ninety degrees by narrow bands or fillets, as shown. Within the inner ring, as shown, is an ornamental volute or scroll similar to the volutes or scrolls in the music-desk *C*. On its outer periphery each inner ring is ornamented by projecting radial tongues, as shown, and each outer ring is ornamented on its outer periphery at each corner of the panel by a ring ornament, as shown. The outer stiles and meeting stiles of the panels *n* are 70 ornamented by longitudinal lines, as shown. The upper edge of the back *I* is finished by an ornamental inuated molding *J*, which in turn is ornamented by projecting pyramidal ornaments, as shown. The upper corners of 75 the back *I* are also ornamented, as shown, by similar pyramidal ornaments and by projecting brackets having on their vertical faces stellated ornaments, as shown.

I claim as my invention—

80

1. The design for an organ-case, as herein shown and described.

2. In an organ-case, the design for the ornamentation of the front board *A* thereof, as shown and described.

85

3. In an organ-case, the design for the ornamentation of the front board *B* of the key-board projection thereof, as shown and described.

4. In an organ-case, the design for the ornamentation of the music-desk *C* thereof, as shown and described.

90

5. In an organ-case, the design for the ornamentation of the end *D* of the key-board projection, as shown and described.

95

6. In an organ-case, the design for the ornamentation of the column *F*, as shown and described.

7. In an organ-case, the design for the ornamentation of the end *E* of the case, as 100 shown and described.

8. In an organ-case, the design for the ornamentation and shape of the balustrade *H*, as shown and described.

9. In an organ-case, the design for the 105 ornamentation of the back *I*, as shown and described.

In witness whereof I have hereunto signed my name in the presence of two subscribing witnesses.

LEVI K. FULLER.
